YARN MOISTENING APPARATUS

Joseph Amon, Clark, N. J.

Application May 4, 1939, Serial No. 271,708

5 Claims. (Cl. 68—19)

This invention relates to the art of knitting machinery and more particularly to the art of yarn moistening devices to be used on machines in the process of knitting to maintain the proper amount of moisture in the yarn or yarns as they travel from the source of supply to the needles.

It is an object of this invention to provide an improved yarn moistening device especially adapted for quick and easy cleaning of the liquid container without the necessity of removing the yarn or yarns from their yarn guiding apertures.

It is a further object of this invention to provide an improved yarn moistening device in which the means guiding the yarn or yarns through the liquid container is removable as a unit without the necessity of removing the yarn or yarns from their yarn guiding apertures.

Other objects and advantages of the invention will appear more fully herein.

The invention consists substantially in the combination, construction and relative arrangement of parts, all as will appear more fully hereinafter, as shown in the accompanying drawings and as finally pointed out in the appended claims.

In the accompanying drawings, wherein has been illustrated the preferred embodiment of the present invention:

30 Figure 1 is a cross-sectional view of the upper rear frame of a straight bar full-fashioned knitting machine with the moistening device in place;

35 Figure 2 is a plan view of the moistening device of Figure 1;

Figure 3 is a sectional view on line 3—3 of Figure 2 looking in the direction of the arrows;

Figure 4 is a sectional view on line 4—4 of Figure 2 looking in the direction of the arrows;

40 Figure 5 is a view similar to Figure 3 and in which the moistening device is shown disassembled;

Figure 6 is a perspective view of a portion of the invention;

45 Figure 7 is also a perspective view of a portion of the invention;

Figure 8 is a longitudinal sectional view taken on the line 8—8 of Figure 3;

Figure 9 is a longitudinal sectional view taken 50 on the line 9—9 of Figure 3;

Figure 10 is a perspective view of the moistening device showing the several parts in separated relation; and

55 Figure 11 is a perspective view showing the device in assembled condition.

Referring now to the drawings and more particularly to Figure 1, the invention is illustrated in position on a full-fashioned knitting machine, the upper rear frame of which is designated by the reference numeral 11 on which is supported the usual yarn conditioning chamber 12 in which one or more cones of yarn 13 are supported. The chamber 12 extends longitudinally of the machine to accommodate the necessary number of yarn cones.

The yarns from the cones 13 pass upwardly from the chamber 12, passing through the guides 14, and as shown at 15, pass to the open faced moistening device or wetting trough 16, also extending longitudinally of the machine and supported, in any suitable manner, by the frame 11 of the full-fashioned knitting machine. The moistening device 16 is here shown as comprising two sections but obviously the number of sections in each device may vary and the number of devices used on each machine may likewise vary dependent upon the number of needle sections in the machine.

The device 16 includes an open face box 17 containing any suitable liquid yarn wetting agent, as clearly appears in Figure 5. Inside the box 17 and extending lengthwise on the longer sides thereof, are the ledges 18 which are spaced a short distance from the top of the box and extend inwardly. The ledges 18 support the yarn guiding means to be described so that the yarns may extend down into the liquid.

Figure 5 shows the yarn guiding means as having been removed as a unit from the box 17 and the ledge 18, while Figure 3 shows the yarn guiding means back in position resting upon the ledges 18 in the box 17. It will be apparent that when the yarn guiding means are removed, as in Figure 5, without the necessity of removing the yarns therefrom as will be explained, that then the box 17 is easily accessible for cleaning and inasmuch as it is often necessary to clean the box 17, this feature of my invention is very important.

The device 16 also includes the yarn guiding means having the rectangular open frame 19 with longitudinally extending ledges 20 extending along the longer sides of the frame and inwardly thereof. The frame 19 is of a size to fit interiorly of the box 17 with the ledges 20 resting upon the ledges 18, as appears most clearly in Figure 3. A rib 21 extends transversely across the frame 19 approximately midway of its length, as appears in Figures 2 and 4. Secured to opposite end walls of the frame 19, as well as to the

rib 21 are the brackets 22 having the supporting ledges 23, as clearly appears in Figure 2, one of these brackets 22 being shown in perspective in Figure 7. The brackets 22 are positioned so that the ledges 23 are spaced a short distance away from the adjacent longer side wall of the frame 19 as clearly appears in said Figure 7, these ledges 23 being further disposed a short distance above the ledge 20.

10 The reference character 24 designates a longitudinal shelf which is supported by the ledges 23 of the brackets 22, the shelf being retained in position on the frame 19 by means of the depending lips 26 and the depending lugs 27 (Figure 6) which fit over the ledges 23, as may be clearly seen in Figure 3. The shelf 24 is adapted to support the usual felt strip for removing excess moisture from the yarns as they travel in contact with and past the felt, it being noted 15 that the shelf 24 is provided along its inner edge with a longitudinally extending upright flange 24a in which are provided a plurality of eyelet guides 24b.

While in the construction illustrated the shelf 24 for supporting the felt strip is shown in the form of a detachable element which is removably supported in position upon the ledges 23 of the brackets 22, it will be understood that this shelf may be formed as an integral part of the removable frame 19, in which event, the shelf, designated 24, would constitute the base of a relatively shallow trough extending lengthwise of the frame 19 immediately adjacent one side wall thereof, the opposite side walls of this trough 30 being provided with a plurality of longitudinally spaced eyelet guides for guiding the yarn or yarns out of the main liquid trough and across the felt supported upon the shelf 24. In either event, whether the felt shelf be formed as an integral part of the frame 19 or as a readily removable element, the outer longitudinally extending edge of the shelf is spaced from the proximate side wall of the frame 19 as well as from the supporting ledge 20 of the latter to provide a free opening 30 (see Figures 3 and 5) through which excess liquid accumulated by the felt strip as the yarns pass thereover may flow back into the box 17 containing the main supply of said liquid.

The glass float tubes are designated by the character 28 and these serve as guides for the yarns to cause them to travel through the liquid in the box 17. The means supporting the glass tubes 28 are the hangers 29, each of which is slotted to removably receive the ends of the float rods and to carry them inside the box 17. The extreme end wall hangers 29 are secured in place on the opposed end walls of the frame 19 by means of the overhanging lips 30a which engage over the upper ends of said end walls, while the intermediate hangers 29 are secured together and are suspended as a unit over the intermediate transverse rib 21 of the frame 19. It will be obvious that the lips 30a may be permanently secured to the frame 19 rather than removably secured as shown. It is preferred, however, to removably secure the hangers 29 in position because in such event the latter may be removed from the frame 19 in order to render the glass tubes 28 accessible for cleaning or replacement without effecting disorganization of the frame 19 with respect to the main box 17.

Suitable eyelets, preferably porcelain, are provided as shown to guide the yarns and specifically these eyelets are in both of the longer side walls of the frame 19, and in the upright portion

of the shelf member 24. A suitable number of these eyelets are provided and the yarns 15 pass through those on the right side of the frame 19 (Figure 3); then down and under the tubes 28, then up and through the eyelets in shelf member 24, then through the eyelets on the other side of the frame, and then on to the yarn guides feeding the yarn to the needles.

It will be noted that all of the yarn guiding means are secured to the frame 19, including the glass tubes 28 for training the yarns through the liquid wetting agent and the felt strip for removing excess liquid from the yarns. Thus, as the frame 19 is removed from the box 17, all of the yarns are carried along therewith out of the box 17 and still threaded through the eyelets, glass tubes, and felt strip means. After the box 17 is cleaned, the frame 19 with the yarns still threaded, may be lowered back in position in the box 17. Thus, it will be seen that with a minimum of effort, the box 17 which requires frequent cleaning, is readily and easily accessible for that purpose, and the trough may be dismantled as shown in Figure 10 without the necessity of cutting or in any way disturbing the threads which pass from their supply source to the knitting machine.

What is claimed as new and useful is:

1. In a yarn moistening device for a full-fashioned knitting machine, in combination, a rectangular container for a liquid yarn wetting agent, a readily removable rectangular frame member supported by said container, and means carried by said frame member for supporting a plurality of longitudinally extending floats within said container for guiding yarns through said liquid.

2. In a yarn moistening device for a full-fashioned knitting machine, in combination, a rectangular container for a liquid yarn wetting agent, a readily removable rectangular frame member supported by said container, means on said frame member for supporting a plurality of longitudinally extending tubular floats within said container for guiding yarns through said liquid, and a longitudinally extending shelf member on said frame member for supporting a felt strip to remove excess moisture from said yarns.

3. In a yarn moistening device for a full-fashioned knitting machine, a rectangular container having inwardly projecting ledges extending longitudinally along opposite side walls of said container, a readily removable rectangular frame member extending within and supported by said container ledges, brackets on said frame member for supporting a plurality of longitudinally extending floats within said container for guiding yarns through said liquid, and additional brackets on said frame member for detachably supporting a longitudinally extending shelf member in position adjacent said floats for supporting a felt strip to remove excess moisture from said yarns.

4. In a yarn moistening device for a full-fashioned knitting machine, in combination, a main container for a liquid yarn wetting agent, a readily removable open frame member supported within the top of said container, means carried by said frame member for suspending a plurality of laterally spaced longitudinally extending yarn guiding elements within said container and a plurality of longitudinally spaced yarn-guiding eyelets in the opposite side walls of said frame member, the arrangement being such that yarns threaded through registering eyelets in opposite walls of said frame member and across said yarn

guiding elements may be raised upwardly and out of said liquid container without necessitating unthreading of the yarns from their guide eyelets.

5. In a yarn moistening device for a full-fashioned knitting machine, in combination, an open-topped container for a liquid yarn wetting agent, a frame adapted to snugly fit within the top of said container with the side walls of said frame extending above the top edges of said container, 10 said upwardly extending side walls of the frame member being provided with a plurality of opposed registering yarn guide apertures, means

carried by said frame member for suspending interiorly of the container a plurality of longitudinally extending laterally spaced yarn guiding element, said frame member and the element supported thereby being separable from the container at will whereby to permit the removal of said frame member and its associated parts including yarns threaded therethrough from the container in order to render the latter clear of said yarns and yarn guiding means for cleaning 10 and other such purposes.

JOSEPH AMON.
